UNITED STATES PATENT OFFICE.

HAROLD JOHNSON, OF BROOKLYN, NEW YORK.

COMBINED DRAWING INSTRUMENT, BOOK-MARK, AND PAPER-CUTTER.

1,078,145.

Specification of Letters Patent.

Patented Nov. 11, 1913.

Application filed August 6, 1912. Serial No. 713,656.

To all whom it may concern:

Be it known that I, HAROLD JOHNSON, citizen of the United States, residing at Brooklyn, in the county of Kings and State of New York, have invented certain new and useful Improvements in Combined Drawing Instruments, Book-Marks, and Paper-Cutters, of which the following is a specification.

10 This invention is a combined drawing instrument, book-mark, and paper cutter, and has for its object the provision of a cheap, simple, and efficient device which may be utilized in various capacities.

15 The invention is fully illustrated in the accompanying drawings and consists in certain novel features of construction and arrangement which will be hereinafter first fully described and then more particularly 20 pointed out in the appended claims.

In the drawings:—Figure 1 is a plan view of my improved device arranged for use as a square; Fig. 2 is a plan view of a portion of the device showing it arranged for use 25 as a T-square; Fig. 3 is a plan view showing the manner of using the device as a book-mark; Fig. 4 is a detail section taken on the line 4—4 of Fig. 1; Fig. 5 is a detail section taken on the line 5—5 of Fig. 1; 30 Fig. 6 is a detail perspective view of a clip employed to secure the main members of the tool together, when it is desired to use the same as a square; Fig. 7 is a detail plan view of the blank from which the pointer 35 is formed; and Fig. 8 is a detail plan view of a portion of the blank from which the main members or branches of the tool are formed.

In carrying out my invention, I employ 40 a pair of limbs or main members 1 and 2 which are constructed of light metal and have straight edges, as clearly shown. A scale 3 is marked along one edge of each member and the opposite edge of each member is constructed with a bead or flange 4 to reinforce the same and also serve as a guide for an index or pointer 5 which is adapted to slide along the limb or member and thereby indicate a measurement taken, 45 or, when the device is utilized as a book-

mark, to accurately mark the point at which the reading stopped.

Each branch or main member of the tool is stamped out of sheet metal with a projecting portion 6 along one edge and the 55 said projecting portion 6 is then folded or doubled over upon the main portion of the blank to constitute the flange or bead 4, the edge of this bead or flange being left free of the main body of the limb or member so 60 that a portion of the index or pointer 5 may project under the said edge and be thereby held to the limb while permitted to slide freely along the same. The ends of this bead are subsequently compressed and intimately united with the main body of the leg or member of the tool so that a stop 65 will be provided to limit the movement of the index or pointer and prevent the detachment of the same from the body and thereby avoid its loss. The said index or pointer is preferably constructed from a blank of the form shown in Fig. 7 in which a pair of longitudinal tongues 7 are connected by a central reduced neck 8, the portions of the tongues immediately adjacent the neck being laterally extended, as indicated at 9, in order to impart an ornamental appearance to the device and also to aid in determining the exact point marked by the 70 indicator. By providing these lateral extensions the neck will appear, by contrast, narrower than it really is and will thus aid the eye in accurately noting the point designated by the index. The outer ends of the 75 tongues 7 merge into integral lateral heads 10 and 11, the head 10 being smaller than the head 11 and being adapted to extend under the free edge of the bead or flange 4, while the head 11 is adapted to be doubled 80 around the flange, as shown in Fig. 5.

In applying the index to the body of the device, the blank is folded at the center of the neck 8 so that the tongues 7 are brought together, after which the said tongues are 85 placed against the opposite faces of the main member, the head 10 is inserted under the bead 4 and a tooth 12 is struck up centrally from the said head. The head 11 is doubled 90 around the flange, and the central portion 100

of said head, shown at 13, is struck out to be engaged by the said tooth 12, so that the two heads will be locked together, and the free edge of the head 11 is bent past the free edge of the bead 4 so as to rest upon the exposed portion of the head 10, as will be readily understood upon reference to Fig. 5. It will thus be seen that I have provided an exceedingly simple and easily applied indicator which may be readily moved along the main member or rule which constitutes a leg or branch of the tool and will be effectually held against accidental release from the said tool.

One end of each branch, main member, or rule is curved, as shown at 14, and the opposite end is reinforced by a bead 15 secured thereto by suitable rivets and constituting a rest against which the other rule or main member of the instrument may be placed so that the two members will be arranged at a right angle, when it is desired to utilize the device as a drawing instrument. A U-shaped plate or clip 16 is secured to the bead 15 and projects beyond the same over the rule or member carrying the said bead, and this clip is adapted to engage over the meeting portion of the co-acting rule or main member of the device, when the tool is used as a drawing instrument. When the device is used as a book-mark, the two members are separated and the said clip is engaged over the edge of the leaf so as to hold the rule thereon, as clearly shown in Fig. 3. To prevent accidental detachment of the two members or rules, when the device is used as a drawing instrument, I employ a clasp consisting of a U-shaped spring plate 17 adapted to fit over the clips 16 and provided on one branch with an inwardly projecting stud or pin 18 adapted to pass through the openings provided therefor in the clips 16 and the main members or rules 1 and 2. When it is desired to use the device as a T-square, the member 1 is shifted along the member 2 to the center thereof and the clasp 17 is then fitted over the clip 16 at the end of the member 1 and the pin or stud 18 is caused to engage an opening 19 provided for that purpose at the center of the member 2, as will be readily understood on reference to Figs. 1 and 2.

The use and advantages of the device are thought to be obvious from the foregoing description, taken in connection with the accompanying drawings. The several elements of the tool may be easily separated and as easily fitted together, and when fitted together, will be securely held in their proper relative positions. When the device is used as a book-mark, the two members are separated and either or both are placed against the leaf of a book with the clips engaging the upper edges of the

leaves and the indicators are then moved so as to register with the line at which the reading stopped. An accurate mark will thus be provided, so that, when the reading is resumed, no time will be lost in finding the proper place at which to start the reading and the book will remain unmarred and unmutilated. Should the leaves of a book or magazine be uncut, either member or rule of the device may be readily run within the fold of the uncut leaves and will quickly separate the same. Either member or rule may be utilized as a straight edge, separately from the other member, so that the device will be found of great convenience to bookkeepers.

The U-shaped clasp 17 may be utilized, when removed from the main members of the tool, as a paper clip or file to hold bills, notes, or other loose sheets by being engaged over the edges of the same.

The several parts of the device are exceedingly simple in their construction, and, as they all may be stamped out of sheet metal, the instrument will be found exceedingly durable without being expensive to produce and without being cumbersome and heavy.

What I claim is:—

1. In a device for the purposes set forth, the combination of a main member having a bead formed along one edge, and an indicator fitting around and close to the member and having inter-locking heads, one of said heads engaging under the free edge of the bead and the other head being folded over and around the bead.

2. In a device for the purposes set forth, the combination of a main member having a bead formed along one edge, and an indicator consisting of a pair of tongues disposed against the opposite sides of the said member and connected by a reduced neck at one side edge of the said member, and interlocking heads formed at the opposite ends of the said tongues, one of said heads engaging under the free edge of the bead and the other head being doubled over and around the bead.

3. In a device for the purposes set forth, the combination of a main member having a bead formed along one edge, and an indicator consisting of tongues fitting transversely against the opposite sides of the said member, a reduced neck connecting said tongues at one edge of the said member, a head at the opposite end of one of the tongues engaging under the free edge of the bead and having a tooth struck up therefrom, and a head at the opposite end of the other tongue doubled over and around the bead and having interlocking engagement with the said tooth.

4. In a device for the purposes set forth,

the combination of main members each provided at one end with a bead adapted to fit against an edge of the other member, and a clip carried by the end of one member and engaging the other member.

5. In a device for the purposes set forth, the combination of main members, a clip carried by the end of one member adapted to engage the other member, and a U-shaped

clasp fitted upon said clip and carrying a 10 stud adapted to pass through the clip and the two members.

In testimony whereof I affix my signature in presence of two witnesses.

HAROLD JOHNSON. [L. S.]
